US0D1049128S

(12) **United States Design Patent** (10) Patent No.: **US D1,049,128 S**
(45) Date of Patent: ** Oct. 29, 2024

(54) **ELECTRONIC DEVICE OR PORTION
THEREOF WITH DISPLAY SCREEN**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Patrick Lee Coffman**, San Francisco, CA (US); **Daniele De Iuliis**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Raymond Sepulveda**, San Jose, CA (US); **Benjamin Andrew Shaffer**, San Jose, CA (US); **Mikael Silvanto**, San Francisco, CA (US); **Andre Souza Dos Santos**, Santa Clara, CA (US); **Christopher J. Stringer**, Woodside, CA (US); **Joe Sung-Ho Tan**, San Francisco, CA (US); **Clement Tissandier**, San Francisco, CA (US); **Eric Lance Wilson**, San Jose, CA (US); **Eugene Antony Whang**, San Francisco, CA (US); **Chun Kin Minor Wong**, Cupertino, CA (US); **Rico Zörkendörfer**, San Francisco, CA (US)

(73) Assignee: **Apple Inc.**, Cupertino, CA (US)

(**) Term: **15 Years**

(21) Appl. No.: **29/807,527**

(22) Filed: **Sep. 13, 2021**

CLAIM

The ornamental design for an electronic device or portion thereof with display screen, as shown and described.

DESCRIPTION

The sole FIGURE is a top view of an electronic device or portion thereof with display screen showing our new design. Oblique line shading illustrates a transparent surface, which is a display screen. The broken lines depict portions of the electronic device which form no part of the claimed design.
